X-RAY TUBE SAFETY DEVICE

Edwin R. Goldfield, University Heights, and Jack Ball, Cleveland, Ohio, assignors to Picker X-Ray Corporation-Waite Manufacturing Division, Inc., Cleveland, Ohio, a corporation of Ohio

Application July 20, 1946, Serial No. 685,095

4 Claims. (Cl. 250—95)

1

This invention relates to improvements in control circuits for X-ray tubes and more particularly to improvements in safety devices for preventing injury to X-ray tubes by overloading the same.

An object of the present invention is to provide means for preventing an overly long exposure combined with an excessive kilovoltage applied to the tube.

Another object of the present invention is to prevent an excessive combination of time of exposure plus the milliamperage load on the tube.

Still another object of the invention is to prevent any excessive combination of time, kilovoltage or milliamperage so as to overload the tube to the point of injury.

Another object of the present invention is to provide control means preventing overloading of the X-ray tube by an excessive combination of kilovoltage together with a second control factor which includes the product of the milliamperage load on the X-ray tube times the number of seconds the tube is energized.

Other objects and advantages of the present invention will be apparent from the accompanying drawings and description and the essential features thereof will be set forth in the appended claims.

In the drawings,

Fig. 1 is an electrical wiring diagram illustrating one form of our device;

Fig. 2 is a wiring diagram showing a modified form of our device.

An X-ray tube will take a definite maximum leading which is a function of the milliamperage, the kilovoltage and the time for a definite load limit. If any one of the above is increased, then it is necessary to decrease at least one of the other two factors.

In Fig. 1 we have shown an auto-transformer 10 supplied with electrical energy from the circuit L1, L2. Suitable taps connect leads 11 and 12 with the primary 13a of a high tension transformer 13. The secondary 13b of this transformer is connected by leads 14 and 15 with the X-ray tube 16 in the usual manner. The mid-portion of the secondary circuit of the transformer is grounded at 17 in the usual manner. An exposure is initiated in the customary manner by closing push button 18 which completes a circuit from L1 through lines 19 and 20 through the push button and line 21 to relay 22 and then through lines 23 and 24 to the mid-point of the auto-transformer. This energizes relay

2

22 attracting the armature 22a so that current flows through line 12 and normally closed armature 25b of relay 25 to the primary 13a of the high tension transformer.

The timing of the exposure is controlled by the space discharge tube 26 which is of the gas-filled triode type having a cold cathode 26a, a plate 26b and a control grid 26c. The power supply for this tube is provided from the circuit

10 L3, L4 to the primary 27a of transformer 27. The secondary of this transformer 27b is provided with a rectifier tube 28 so that rectified current is supplied to the leads 29 and 30. The circuit of the control grid 26c of the timer tube includes

15 resistance 31, condenser 32, and a time selector switch 33 having a series of limiting resistors 33a, 33b, 33c and 33d. The connecting lines 34 and 36 are tapped into variable resistance 37 so as to apply the desired voltage on grid 26c.

20 Means is provided for short-circuiting condenser 32 up to the moment that an exposure is initiated. This comprises lines 38, 39, normally closed armature 22b of relay 22, and lines 40, 29 and 41. When relay 22 is energized to start an exposure,

25 armature 22b opens this short circuit of the condenser. Then, the condenser begins to charge, the rate depending, among other things, upon the position of the time selector switch 33. As soon as the voltage of condenser 32 reaches a

30 critical value there is a breakdown between the control grid 26c and the cathode 26a, thus firing the tube 26. This immediately carries over to the circuit of plate 26b and acts through the plate circuit, presently described, to energize relay 25 which opens the normally closed armature 25b stopping the exposure.

It is a well known characteristic of the type of tube shown at 26 that the firing of such a tube is dependent not only upon the voltage of grid 26c, but on the voltage of plate 26b also. In other words, there is an inter-relationship be-

35 tween the voltage of the grid and plate, either of which will cause the tube to fire. We make use of this characteristic of the tube to introduce

40 factors responsive to variations in the kilovoltage and milliamperage load applied to X-ray tube 16 in order to control the firing of tube 26. It is obvious that our invention might be applied to 45 modify the firing of tube 26 either upon variations of kilovoltage alone or of milliamperage alone, but we prefer to apply corrections for both of these factors at the same time.

In the circuit of plate 26b are line 42, relay 25, line 43, secondary 44a of transformer 44, line 45 and secondary 46a of transformer 46.

The transformer 44 provides a corrective factor responsive to variations in the kilovoltage applied to the X-ray tube. To this end, the primary 44b of the transformer 44 is connected across lines 11 and 12 with the variable resistor 47 to set the desired current for the transformer primary 44b. Thus, as the kilovoltage controlled through lines 11 and 12 varies up or down the current in the transformer secondary 44a will vary up or down in like manner, so as to provide a corrective factor in the circuit of plate 26b. If the kilovoltage increases beyond a predetermined point, then the voltage on plate 26b will increase and will fire tube 26 so as to terminate the exposure.

The corrective factor for milliamperage of X-ray tube 16 is applied in the plate circuit of tube 26 by means of the secondary 46a of transformer 46 as previously mentioned. The primary 46b of this transformer is in circuit with the filament transformer for the X-ray tube. This circuit includes lines 48 and 49, primary 50a of the filament transformer 50, line 51, primary 46b of transformer 46 and line 19. Since the load on the X-ray tube is roughly proportional to the current supplied to the primary 50a of the filament transformer, the transformer 46 will be responsive to variations in the load on the X-ray tube, and through its secondary 46a will supply a corrective factor in the circuit controlling plate 26b. Thus, as the load on the X-ray tube increases, the voltage on plate 26b will increase and upon reaching a predetermined level will fire tube 26 and terminate the exposure.

To limit the filament current corresponding to the time selected at switch 33, a gang switch 52 is provided which is operated in unison with switch 33, such connection being indicated by the broken line 53. A shunt resistor 54 is provided across the transformer primary 46b, the various taps of which are connected to similar taps 52a, 52b, 52c, 52d and 52e of the gang switch 52. Thus, corresponding to a definite time setting picked off by switch 33, a filament current limiting resistor is picked off by switch 52 which governs the amount of voltage to be introduced into the plate circuit of the timer tube 26.

The transformers 44 and 46 are so constructed and adjustable resistances so selected, that the voltages introduced by them into the circuit of plate 26b cause the tube 26 to fire whenever excessive kilovoltage or milliamperage, or a combination of both, is introduced into the X-ray tube control circuits, always in correspondence to the time of tube exposure.

It should be noted that the compensating voltages in the control circuit for tube 26 are always on, even though an exposure is not initiated. Therefore, tube 26 may fire and open relay 25 at the armature 25b thereof before push button 18 is closed, in an attempt to start the exposure. This means that should the factors for the exposure be chosen so as to impose too great a load upon the X-ray tube, then it would be impossible to start an exposure.

Preferably, we provide an indicating device 55, 65 such as a lamp or the like, to show that relay 25 is open and that the exposure chosen would impose too great a load upon the X-ray tube. To this end, lamp 55 is in circuit with lines 24, 48, 56, 57 and 19 when relay armature 25a is attracted by the energization of relay 25.

Fig. 2 shows a modification of Fig. 1 wherein similar parts having similar functions have been given the same reference characters and only the differences will be explained here. The purpose

of Fig. 2 is to provide a correction factor which more directly is responsive to the milliamperage applied to the X-ray tube 16. For this purpose, the correction factor for the load on the X-ray tube is supplied through transformer 58, whose secondary 58a occupies the same place in the control circuit of plate 26b as that occupied by the transformer secondary 46a previously described. The primary 58b of this transformer is connected by lines 59 and 60 in the central secondary circuit of high tension transformer 13. Here, as in the previously described modification, the shunt resistor 54 is connected to suitable taps on gang switch 52 so that a definite load factor permissible on the X-ray tube is selected with each movement of the timer switch 33. In this modification, the filament transformer 61 has a primary 61a connected with the source L5, L6, in any suitable manner, as the filament transformer is not directly concerned in the safety control circuit in this modification of our device.

All of the other factors of Fig. 2 correspond to those described in Fig. 1 and any change in kilovoltage or load applied to the X-ray tube provides a corresponding variation in the firing of tube 26 which opens the relay 25b of relay 25 to terminate the exposure. The armature 25a and the indicating lamp 55 have been omitted from Fig. 2, but obviously, they may be used as shown in Fig. 1, if desired.

In Figs. 1 and 2, we have shown the auto-transformer 10 with energizing circuit L1, L2, and a self-rectified unit. However, those skilled in this art will recognize that in most cases the type of X-ray unit used would be provided with a four-valve-bridge-circuit. Our invention may be used, however, using either a self-rectified circuit, a half-wave rectified circuit, or a full-wave rectified bridge circuit, as will be readily understood.

What we claim is:

1. In the combination of an X-ray tube having a high tension tube energizing circuit and a filament energizing circuit including a filament transformer having primary and secondary windings, switch means controlling energization of said X-ray tube, a space discharge tube operatively connected with said switch means, said space discharge tube having control electrode means, a variable resistance timing means in circuit with said control electrode means, a control transformer having a primary winding in series circuit with said filament transformer primary winding and having a secondary winding, and said control transformer secondary winding in electrical circuit with said control electrode means and varying the voltage applied to the latter.

2. In the combination of an X-ray tube having a high tension tube energizing circuit including a high tension transformer having primary and secondary windings and including a filament energizing circuit having a filament transformer with primary and secondary windings, means controlling energization of said X-ray tube including a space discharge tube having control electrode means, timing means for selecting a variable resistance, a first control transformer having a primary winding in circuit with said high tension transformer primary winding, a second control transformer having a primary winding in circuit with said filament transformer primary winding, each of said control transformers having a secondary winding, and said secondary windings of said control

transformers and said variable resistance in electrical circuit with said control electrode means.

3. In the combination of an X-ray tube having a high tension tube energizing circuit including a high tension transformer having a primary winding and having a secondary winding with a central secondary grounded circuit, means controlling energization of said X-ray tube including a space discharge tube having control electrode means, timing means for selecting a variable resistance, a control transformer having a primary winding in said central secondary grounded circuit and having a secondary winding, and said control transformer secondary winding and said variable resistance in electrical circuit with said control electrode means.

4. In the combination of an X-ray tube having a high tension tube energizing circuit including a high tension transformer having a primary winding and having a secondary winding including a central secondary grounded circuit, means controlling energization of said X-ray tube including a space discharge tube having control electrode means, timing means for selecting a variable resistance, a first control transformer having a primary winding in circuit with said high tension transformer primary winding,

a second control transformer having a primary winding in said central secondary grounded circuit, both of said control transformers having secondary windings, and said control transformer secondary windings and said variable resistance in electrical circuit with said control electrode means.
